UNITED STATES PATENT OFFICE.

BARTON S. SNOW, OF BATAVIA, ILLINOIS, ASSIGNOR TO T. W. SNOW CONSTRUCTION COMPANY.

HOISTING MECHANISM.

Application filed April 12, 1924. Serial No. 706,057.

To all whom it may concern:

Be it known that I, BARTON S. SNOW, a citizen of the United States, residing at Batavia, in the county of Kane and State 5 of Illinois, have invented a new and useful Improvement in Hoisting Mechanism, of which the following is a specification.

My invention relates, as to certain features thereof, generally to machines involving a member adapted to be moved in opposite directions, with means for effecting such movements of the member automatically, such as for example, automatically operating hoists, planers and other structures; and 15 as to the other features thereof to hoists and the like machines.

My objects, generally stated, are to provide for the operation of a member adapted to be moved in opposite directions, in such 20 a manner that a sufficient interval of time will lapse between the engagement of the driving means therewith for moving it in one direction and the engagement of such means for moving it in the opposite direction; and that such intervals will occur at the proper time relative to the operation of such member throughout the continued 25 operation of the latter; to provide, more particularly, in connection with the employment of my invention in hoist mechanism, novel, simple, positive and safely operating means for automatically operating the hoist in opposite directions, with the lapsing of the desired intervals of time between the automatic stopping of the hoist in its movement in one direction and the automatic starting of the hoist to move it in the opposite direction; to provide means whereby the member referred 30 to may, under the control of the operator, be caused to make one complete reciprocation and thereupon automatically stop, as for example in the case of a hoist, to cause the hoist to move a load to dumping position 35 and thereafter automatically return to filling position; to provide a novel, simple and positively operating construction of brake-mechanism which shall be conditioned automatically for preventing the drum, on 40 which the hoisting cable is moved, from reversely rotating, when being driven in either direction, under the action of the load, in the event of failure of the power for driving the drum, or other conditions 45

occurring, which would permit the load to 55 rotate the drum, unless restrained; and other objects as will be manifest from the following description.

I have devised my improvements for use more particularly in connection with hoisting machines, such for example, as the kind shown in U. S. Letters Patent No. 963,384, granted to R. A. Ogle, July 5th, 1910, and have therefore chosen to illustrate them as embodied in a machine of this general construction, though without intending to limit the invention thereto.

Referring to the accompanying drawing:—

Figure 1 is a view in side elevation of a 70 hoisting machine of the general character shown in said Letters Patent, and embodying my improvements. Figure 2 is a rear view of the machine. Figure 3 is a section taken at the irregular line 3—3 on Fig. 1 and viewed in the direction of the arrows. Figure 4 is a section taken at the irregular line 4—4 on Fig. 3, and viewed in the direction of the arrows. Figure 4^a is a broken section taken at the line 4^a on Fig. 4 and viewed in the direction of the arrow. Figure 4^b is a section taken at the line 4^b on Fig. 4 and viewed in the direction of the arrow. Figure 5 is a section taken at the line 5 on Fig. 1 and viewed in the 75 direction of the arrow. Figure 6 is a broken section taken at the irregular line 6—6 on Fig. 1 and viewed in the direction of the arrows. Figure 7 is a broken section taken at the line 7 on Fig. 6 and viewed in the 80 direction of the arrow. Figure 8 is a section taken at the line 8 on Fig. 2 and viewed in the direction of the arrow. Figure 9 is a section taken at the line 9—9 on Fig. 1 and viewed in the direction of the arrows; and 85 Figure 10, a broken perspective view of the latch mechanism for controlling the repeated operations of the hoist.

As a preface to the following description, it may be stated that the hoist as 100 shown, is adapted to be employed for the operation of a pair of buckets (not shown) moving in opposite directions, or a single bucket, in which latter case the cable at the end thereof in connection with the bucket, carries a counterweight which is heavier 105 than the empty bucket on the other end of the cable, the buckets, where two are em-

ployed, being so disposed with relation to loading and dumping points that one bucket is down in position to be loaded while the other bucket extends in elevated, dumping, position.

The frame 11 of the hoist comprises two side members 12 and 13 spaced apart as represented, and provided at their upper ends with bearings 14 and 15 in which two shafts 16 and 17, extending transversely of the machine, are journaled, respectively. The shaft 16 carries, between its ends, a drum 18 about which the cable (not shown) to the opposite ends of which the buckets referred to would be attached, is wound. The drum 18 is rotatable on the shaft 16, it being adapted to be clutched to the latter by means of a clutch (not shown) operated through the medium of a lever 16^a fulcrumed at its rear end on the frame of the machine. The drum 18 has rigidly secured thereto a sprocket 19 for a purpose hereinafter described.

The drive shaft, represented at 20, is journaled in bearings 21 at the opposite sides of the frame 11, and carries toward its opposite ends pinions 22 and 23 which are freely rotatable about the shaft 20 and are adapted to be alternately clutched to this shaft by clutches 24 and 25, respectively, operated in a well-known manner through the medium of a horizontally swinging lever 26 fulcrumed between its ends, as indicated at 27, on a stationary sleeve 28 surrounding a shaft 29 journalized in bearings 30 on the frame 11 at opposite sides thereof and held against longitudinal movement thereon by collars 31 on the shaft 29. The clutches 24 and 25 in the particular construction shown are each formed of two members one of which is splined to the shaft 20 and is movable lengthwise of the latter by operating the lever 26 and the other of which is rotatable on the shaft 20, (the pinions 22 and 23 being rigid on the last-referred-to members of the clutches) and becomes clutched to the shaft 20 through the medium of the said splined clutch members co-operating therewith.

The shaft 17 carries at one end a gear 32 rigidly secured thereto and meshing with the pinion 23 and a pinion 33 fixed on the shaft 29, and at its opposite end a pinion 34 meshing with a gear 35 fixed on the shaft 16, the shaft 29 also carrying a pinion 36 secured thereto and meshing with the pinion 22. Thus when the clutch 25 is thrown in, the gears 22, 36, and 33 operate idly and the gear 32 is driven from the pinion 23 direct for driving the shaft 16 and its drum 18 in one direction, whereas when the clutch 24 is thrown in, the gear 32 is driven through the medium of the gears 22, 36 and 33, thus reversing its direction of movement and that of the shaft 16 and the drum carried thereby.

The hoist, as shown, is provided with means for controlling the movement of the drum 18 in opposite directions and applying a brake to the drum in the event of the breaking of a part of the machine, or the failure of power, which would allow the drum to run free, these means being automatic and comprising the following described parts: Journaled in bearings 37 on the frame sides, is a shaft 38 carrying a box-cam 39 presenting the surfaces 39^a and 39^b the latter surrounded by the former. The surface 39^a throughout a portion thereof is in the form of a cam 39^c and its remaining portion 39^d is concentric with the shaft 38. The surface 39^b at the portion 39^a thereof opposite the cam-surface 39^c is in the form of a cam and its remaining portion 39^e is concentric with the shaft 38. Straddling the shaft 38 at a yoke-portion 40 to be crosswise movable thereon, is a rod 41, the rear end of which terminates in a yoke 41^a pivoted at its arms 41^b to the bell crank 26, at 41^c, the yoke 40 being provided with a pin 40^a carrying a roller 40^b which extends into the endless groove bounded by the surfaces 39^a and 39^b and is adapted to co-operate with these surfaces, the diameter of the roller 40^b being less than the width of this groove, as shown, and the arrangement being such that in the rotation of the cam 39 in opposite directions the roller 40^b is engaged, in succession, by the cams 39^c and 39^e, causing, in the rocking of the shaft 38 in one direction, when one of the clutches 24-25 is in, the movement of the clutch mechanism to neutral position, and in the rocking of this shaft in the opposite direction when the other of the clutches is in, the movement of the clutch mechanism to neutral position. Rotatably mounted on the shaft 38 is a yoke-shaped frame 44, opposite sides of which contain longitudinally extending slots (not shown) and corresponding with the slots in the corresponding yoke member of said patent, these slots serving as guides for the ends 45 of a pawl device 46 having screw-threaded connection with the threaded portion 47 of the shaft 38 within the confines of the frame 44. The frame 44 is rigid with a sprocket wheel 48 connected by a chain 49 with the sprocket wheel 19 on the drum 18 whereby in the rotation of this drum the yoke 44 and the pawl device 46 are rotated and the latter is carried along the shaft 38 by reason of its threaded connection therewith, in one direction or the other in Fig. 2 depending on the direction in which the drum 18 is rotated. The pawl device 46 is formed on its opposite faces with oppositely disposed shoulders 50 and 51 which are adapted to alternately engage with shoulders 52 and 53, respectively, formed on dogs 54 and 55 rigidly secured to the shaft 38, but adjust-

able lengthwise thereon by clamping means indicated at 56 and 57, respectively, whereby engagement of the shoulders 50 and 51 with their respective cooperating shoulders 52 and 53 operate to rock the shaft 38 for moving the drive-shaft-clutch mechanism, and comprising the clutches 24 and 25, to a normal, inoperative, neutral position for interrupting the drive of the machine as is 10 hereinafter more fully explained.

The braking mechanism referred to for the drum comprises a pair of brake-shoes 58—59 located at opposite sides of the shaft 16 and opposing a flange 60 on the drum, 15 these shoes being pivotally supported at 61 and 62, on the upper ends of levers 63 and 64 pivoted at their lower ends, as represented at 200 and 201, respectively, to lugs 200^a and 201^a rising from a plate 200^b shown as 20 bolted to a flooring. The levers 63 and 64 are pivotally connected, between their ends, with the outer ends of links 202 and 203, respectively, which are pivotally connected, at 204, with upwardly-extending arms 205, 25 rigid on a shaft 206 journaled in the frame 11 at opposite sides of the machine. The shaft 206 is operated, through the medium of the shaft 38, by means of a link 206^a pivotally connected at one end, as indicated 30 at 206^a, to an upwardly-extending arm 206^b rigid on the shaft 206 and at its opposite end rigidly connected, as indicated at 206^c with the part 41^a. The parts just described are so constructed and arranged, as shown, 35 that when the arms 205 incline in the direction shown of the arm 209 in Fig. 1, the brake-shoes 58—59 do not interfere with the free rotation of the drum 18 in clockwise direction in this figure, but in the case of 40 reverse rotation of the drum, by action of the load, the shoe 58 wedges against the flange 60 and arrests rotation of the drum 18, and when the arms 205 incline in the opposite direction, in which position they 45 extend when the clutch 24 is in, the brake-shoes 58—59 do not interfere with free action of the drum in counterclockwise direction in Fig. 2, but in case of reverse rotation of the drum, under the action of a load, the 50 shoe 59 will wedge against the flange 60 and arrest rotation of the drum.

The mechanism in so far as it has been described, constitutes means whereby the clutch mechanism and comprising the 55 clutches 24 and 25, is automatically moved to a neutral position upon the conclusion of a predetermined number of revolutions required to effect the desired reciprocation of the buckets of the hoist, there being provided for co-operation with the mechanism described other mechanism which operates automatically to effect reverse rotation of the drum 18 following the lapsing of the desired time interval required, in the case 60 of hoisting mechanism, to effect the loading

and dumping of the buckets, a description of this mechanism, according to one embodiment of my invention, being as follows:

The drive shaft 20 carries at one end thereof, and rigid thereon, a worm 65 for 70 co-operation with a mutilated worm-wheel 66 pinned on one end of a shaft 67 journaled in a bearing 68 on a bracket 68^a hung at bearings 68^b on the shaft 20, the forward end of this shaft being provided with a collar 69 rigid thereon with its periphery in the form of a cam and affording an abrupt shoulder 70, the axis of the shaft 67 extending at a right angle to the axis of the shaft 20. The bracket 68^a is held in the desired 80 position by a bar 93 connected at one end to the shaft 206 by a pivoting screw 95 in the end of this shaft, and at its forward end to the bracket 68^a as indicated at 94. The worm-wheel 66, is mutilated at diamet- 85 rically opposed points, as represented at 71 and 72, the length of these mutilated portions in a direction circumferentially of the worm-wheel being in each case slightly greater than the length of the worm 65 so 90 that when either of these mutilated portions register with the worm 65, the worm-wheel 66 will be out of driving engagement therewith. The worm-wheel 66 is provided with a crank pin 73 on which the outer end of 95 a rod 74 is journaled, this rod being rigidly connected with one end of a cylinder 75, the other end of this cylinder containing a hollow plug 76 through which a rod 77 extends, the inner end of this rod being provided 100 with a rigid head 78. A coiled spring 79 is confined between the head 78 and the end of the cylinder 75 at which the latter is connected with the rod 74, and a coiled spring 80 is confined between the head 105 78 and the plug 76, the outer end of the rod 77 being operatively connected with an arm 81 depending from the clutch-shifting lever 26. The connection just referred to involves the aperturing of the arm 81, as 110 represented at 82, through which the rod 77 extends, and the provision of stops, in the form of nuts 83 on this rod at opposite sides of the arm 81. The worm-wheel 66 is pro- 115 vided at diametrically opposed points there- on, with laterally-projecting pins 84 and 85 with which co-operate a stop bar 86 slidably mounted at its rear end in an opening 87 in the bracket 68^a, a coiled spring 89, sur- 120 rounding the bar 86 and engaging at one end with a stop surface 90 on this bar and at its other end with the front face of the bracket 68^a, operating to exert force on this bar tending to move it to the right in Fig. 7 out of a position in which it extends into 125 the path of movement of the stops 84 and 85 in the rotation of the worm-wheel 66 as hereinafter described. The forward end of the bar 86 is provided with a laterally-ex- 130 tendsing pin 91 which is slidable, with the

bar 86, in a slot 92 in the bar 93. The inner end of the pin 91 carries a roller 96 which, under the action of the spring 89, bears against the periphery of a cam 97, rigid on the shaft 206, the cam portion of this cam being of reversed curvature and presenting the convex upper and lower cam portions 98 and 99 and the intermediate concave portion 100.

- 10 The operation of the apparatus is as follows: The machine is shown in the position it assumes during the driving of the drum 18 in clockwise direction in Fig. 1, the drive being from the shaft 20 through clutch 25, 15 gears 23 and 32, shaft 17, gear 34, gear 35 to drum 18, thus rotating the yoke 44 in clockwise direction in Fig. 1, which causes the pawl device 46 to move along the yoke 44 to the left in Fig. 2, toward the dog 54. 20 In the continued movement of the parts as stated, the shoulder 50 engages the shoulder 52 on the dog 54, thus rotating the shaft 38 and cam 39 in clockwise direction in Fig. 1, with the result, by reason of the engagement 25 of cam-surface 39^e with roller 40^b, of forcing the rod 41 to the left in Fig. 3 to a position in which both of the clutches 24 and 25 are in neutral position, whereupon the drum 18 ceases to rotate. The movement of 30 the rod 41, as stated, effects, through the link 206^a the rocking of the shaft 206 in counter-clockwise direction in Fig. 1 to a position in which the low part 100 of the cam 97 extends opposite the roller 96, 35 thereby permitting the spring 89 to shift the locking bar 86 to the right in Fig. 6 to a position in which this bar is withdrawn from the position in which it extends into the path of movement of the pins 84 or 85. 40 It should be here stated that in the position of the parts as shown in the drawings and which is the position occupied by them during the rotation of the drum 18 in clockwise direction as stated, the mutilated portion 45 71 of the worm wheel 66 registers with the worm 65 as shown in Fig. 2, in which position the pin 85 engages the lock-bar 86; and the crank pin 73 occupies a position below, and slightly to the right of, the center of the shaft 67.

In the moving of the clutch mechanism to neutral position, as above described, in which operation the lock-bar 86 is withdrawn as stated, the rod 77 is moved to the left in Fig. 2, by reason of its connection with the bell-crank 26, the spring 80, by engagement therewith of the head 78, being under a tension sufficient for shifting the rod 74 to the left in this figure, with the result that the worm-wheel 66 is rotated in clockwise direction in Fig. 2, into a position in which the teeth on its periphery engage with the continuously rotating worm 65, whereupon the worm wheel 66 is rotated by 60 this worm one-half of a revolution to a posi-

tion in which the mutilated portion 72 of the worm-wheel 66 registers with the worm 65. As the pin 73 is carried to the left in Fig. 2, by the rotation of the worm-wheel 66 as stated, the rod 74 and cylinder 75 are forced to the left in Fig. 2 and as this movement continues a force is directed against the rod 77 through the cylinder 75, spring 79 and head 78, operating to force the rod 77 to the left in Fig. 2 and moving the clutch mechanism from a position in which both of the clutches 24 and 25 are in neutral position, to a position in which the clutch 24 is in operative position. The arrangement of the parts is such, as shown, 75 that the cam-disk does not obstruct the movement of the clutch mechanism and the parts directly connected therewith as just stated, in which movement of the clutch mechanism the cam 97, by reason of the link connection 206^a, is swung downwardly to a position in which its high point 98 engages the roller 96 thereby again forcing the lock-bar 86 to the left in Fig. 1, against the resistance of the spring 89, to a position in which it obstructs the movement of the pin 84 in which position the mutilated portion 72 of the worm-wheel 66 registers with the worm 65, in which position the lock-bar 86 prevents the spring device connecting the arm 81 with the worm-wheel 66, from rotating the worm-wheel out of a position in which the mutilated portion 72 of the worm wheel 66 registers with the worm 65.

The moving of the clutch 24 to clutched position as stated operates to clutch the gear 22 to the shaft 20 whereupon the drive of the drum 18 is reversed, it being then driven from the shaft 20, clutch 24, gears 22, 36, shaft 29, gear 33, gear 34 and gear 35. The operation of the drum in reverse direction as stated operates to drive the shaft 38 in a direction opposite to that hereinbefore described, thereby rotating the yoke 44 in counterclockwise direction in Fig. 1 which causes the pawl device 46 to move along the yoke 44 to the right in Fig. 2, toward the dog 55. In the continued movement of the parts as stated, the shoulder 51 engages the shoulder 53 on the dog 55, thus rotating the shaft 38 and cam 39 in counterclockwise direction in Fig. 1, with the result, by reason of the engagement of cam-surface 39^e with roller 40^b, of forcing the rod 41 to the right in Fig. 3 to a position in which both of the clutches 24 and 25 extend in neutral position, whereupon the drum 18 ceases to rotate. The movement of the rod 41, as stated, effects, through the link 206^a, the rocking of the shaft 206 in clockwise direction in Fig. 1 to a position in which the lower part 100 of the cam 97 extends opposite the roller 96, thereby permitting the spring 89 to shift the locking bar 86 to the right in Fig. 6 to a position in which this bar is withdrawn

from the position in which it extends into the path of movement of the pins 84 or 85. In the moving of the clutch mechanism to neutral position, as above described, in which operation the lock-bar 86 is withdrawn as stated, the rod 77 is moved to the right in Fig. 2, by reason of its connection with the bell-crank 26, the spring 79, by engagement therewith of the head 78, being under a tension sufficient to shift the rod 74 to the right in this figure, with the result that the worm wheel 66 is rotated in clockwise direction in Fig. 2, into a position in which the teeth on its periphery engage with the continuously rotating worm 65, whereupon the worm wheel 66 is rotated by this worm one half of a revolution to a position in which the mutilated portion 71 of the worm wheel 66 registers with the worm 65. As the pin 73 is carried to the right in Fig. 2, by the rotation of the worm wheel 66 as stated, the rod 74 and cylinder 75 are forced to the right in Fig. 2 and as this movement continues a force is directed against the rod 77 through the cylinder 75, spring 80 and head 78 operating to force the rod 77 to the right in Fig. 2 and moving the clutch mechanism from a position in which both of the clutches 24 and 25 are in neutral position, to a position in which the clutch 25 is in operative position. The arrangement of the parts is such as shown, that the cam disk does not obstruct the movement of the clutch mechanism and the parts directly contacted therewith, as just stated, in which movement of the clutch mechanism, the cam 97, by reason of the link connection 206^a, is swung upwardly to a position in which its high point 99 engages the roller 96 thereby again forcing the lock-bar 86 to the left in Fig. 1, against the resistance of the spring 89, to a position in which it obstructs the movement of the pin 85 in which position the mutilated portion 71 of the worm wheel 66 registers with the worm 65, in which position the lock-bar 86 prevents the spring device connecting the arm 81 with the worm wheel 66, from rotating the worm wheel out of a position in which the mutilated portion 71 of the worm wheel 66 registers with the worm 65.

It will thus be understood from the foregoing that the tension device interposed between the clutch mechanism and the worm wheel 66 operates alternately to exert a pushing and pulling force on the clutch mechanism to move it alternately in opposite directions from neutral position, thereby to effect repeated automatic reversing of the drum 18, and with the desirable time interval between the arresting of the rotation of the drum 18 in one direction and the starting of the reverse rotation of the drum.

The parts of the structure are preferably so constructed and arranged that when the clutch 25 is in clutched position (the position shown in the drawings), the spring 80 will be under a tension sufficient to hold the pin 85 against the stop bar 86 as shown in Fig. 2; and when the clutch 24 is in clutched position, in which position of the parts the pin 73 would occupy a position diametrically opposed to that shown in Fig. 2, the spring 79 will be under such tension as to hold the pin 84 against the stop bar 86.

Referring to the brake mechanism described for the drum 18, this mechanism in the position shown in the drawing permits the drum 18 to freely rotate in clockwise direction in Fig. 1, but should the drum start to rotate in the opposite direction, with the parts in the position shown in the drawings, as for example under the action of a loaded bucket, should an accident occur or should the power be cut off, the brake-shoe 58, by reason of the inclination of the lever 63 as shown in Fig. 1, will immediately grip the drum-flange 60 and lock the drum against rotation. The arms 205, being connected with the shaft 206, when the latter is rotated counter-clockwise in Fig. 1 to a position in which the high part 98 of the cam 97 is in engagement with the roller 96, in which position the clutch 24 is in operative position, these arms will extend to the left, in Fig. 1, of the shaft 206 and the lever 64 will incline to the left in this figure, and thus position the brake mechanism for the gripping of the flange 60, by the shoe 59, in case of accident, or failure of power, which would permit the drum to reverse its rotation under the load therein. Thus the brake mechanism is automatically shifted into proper position for automatically braking the drum, responsive to the alternate clutching and unclutching of the clutches 24 and 25.

The provision of the cam 39 for operating the rod 41 through the pin and roller 40^a and 40^b, is for the purpose of insuring against the overflow of the clutch-mechanism through neutral position by the action of the drum 18 in the event of overrun of the drum after the latter has moved the clutch-mechanism to neutral position. It will be noted that when the clutch 25 is in driving position, as shown in the drawings, the roller 40^b is in engagement with the cam-surface 39^c and when the cam 39 is rotated in clockwise direction in Fig. 4^b by the engagement of the tooth 50 with dog 52, the cam 39^c engages roller 40^b and shifts the clutch mechanism to neutral position, the concentric surface 39^f permitting the drum 18 and cam 39 to continue partial rotation, by overrun, without disturbing the position of the clutch mechanism. The

width of the groove between the surfaces 39^a and 39^b permits the clutch 24 to be automatically moved into driving position by the action of the worm and gear mechanism 5 described, which shifts the roller into close proximity to the surface 39^a. When the cam 39 is reversely rotated by the shoulder 51 engaging dog 53, the cam-surface 39^b engages the roller 40^b and returns the clutch 10 mechanism to neutral position, the concentric surface 39^a permitting overrun of the drum 18 and cam 39 in counterclockwise direction in Fig. 1 without moving the clutch mechanism out of neutral position.

15 The machine, as shown, is provided with means, under the control of the operator, whereby the drum may be caused to automatically stop following its automatic operation first in one direction and then in 20 reverse direction, these means comprising the shoulder 70 on the sleeve 69 and a co-operating lever 101 fulcrumed on the frame of the machine at 102 and provided with a portion 103 which, when the lever is swung 25 downward from the position shown in Fig. 10, upon unhitching it from the hook 104 pivoted at 105 on the frame, extends with the path of movement of the shoulder 70 and restricts the worm-wheel 66 to one 30 complete revolution.

It may be found desirable, or sufficient for practical operation, under some conditions, or in case of mechanism embodying my invention for certain uses, to omit the direct 35 connection between the shaft 38 and the shifting clutches 24 and 25 and comprising the rod 41 (which direct connection, however, is advantageous where it is desired to effect quick release of the clutches) and rely 40 upon the action of the tension-device-control mechanism described and of which the worm 65 and the worm wheel 66 are parts, for shifting the clutches from a position in which the drum 18 is rotated in one direction 45 to a position in which this drum is rotated in the opposite direction, this being possible as the tension device in either of the driving positions of the clutches is under a tension, in accordance with the preferred 50 embodiment of my invention, sufficient to rotate the worm wheel 66 into mesh with the worm 65, immediately upon withdrawal of the stop-bar 86.

It is desirable that the machine be provided with means whereby manual control of the clutches may be effected if desired, and to this end I provide a lever 211 which is journaled on shaft 38 and the lower depending end of which is pivotally connected 60 at 210 with one end of a link 207 the other end of which is pivotally connected at 208 with an upwardly-extending arm 209 fixed on the shaft 206^a. In the use of the hand control, where the springs 79—80 are relatively stiff, as is desired, the link 74 would

be disconnected from the gear 66 to relieve the resistance afforded thereby to the throwing of the clutches by hand, and the link 41 may, or may not be disconnected as desired.

While I have illustrated and described a particular embodiment of my invention, and suggested certain modifications thereof, I do not wish to be understood as intending to limit it thereto as the same may be otherwise variously modified and altered and the invention embodied in other forms, without departing from the spirit of my invention. What I claim as new, and desire to secure by Letters Patent, is:

1. The combination of a driving member, mechanism driven thereby and including a second member adapted to be moved in opposite directions and means adapted to drive said second member from said driving member in opposite directions and movable to neutral position, and means operating automatically upon said first named means to cause the latter to operate said second member automatically in a reverse direction including a device for automatically operating on said first named means to cause the latter to be in neutral position in which said driving member is out of driving engagement with said second member and a tension device having an element formed of relatively movable parts with interposed springs, one of which latter, in the movement of said first-named means to neutral position, is caused to become tensioned, and mechanism controlled by said element in said tensioned condition and operating, when actuated, to cause the other of said springs to become tensioned and exert a force on said first named means for moving the latter out of neutral position.

2. The combination of a driving member, mechanism driven thereby and including a second member adapted to be moved in opposite directions and means adapted to drive said second member from said driving member in opposite directions and movable to neutral position, and means operating automatically upon said first-named means to cause the latter to operate said second member automatically in a reverse direction including a device for automatically operating on said first-named means to cause the latter to be in neutral position in which said driving member is out of driving engagement with said second member, a driving worm, a worm wheel adapted to mesh with said worm and having a mutilated portion normally registering with said worm, and means operatively engaging said worm wheel and said first-named means and operating when said first named means are moved to neutral position to exert a driving force on said worm wheel for meshing the latter with said worm and under the

action of said worm wheel to exert thereafter force on said first-named means to condition the latter for driving said second member in said reverse direction.

5. 3. The combination of a driving member, mechanism driven thereby and including a second member adapted to be moved in opposite directions and means adapted to drive said second member from said driving member in opposite directions and movable to neutral position, and means operating automatically upon said first-named means to cause the latter to operate said second member automatically in opposite directions including a device for automatically operating on said first-named means to cause the latter to be in neutral position in which said driving member is out of driving engagement with said second member, a driving worm, a worm wheel adapted to mesh with said worm and having a mutilated portion normally registering with said worm, and a tension device operatively engaging said worm wheel and said first-named means and operating when said first-named means are moved to neutral position to exert a driving force on said worm wheel for meshing the latter with said worm and under the action of said worm wheel to exert thereafter force on said first-named means to condition the latter for driving said second member in said reverse direction.

4. The combination of a driving member, mechanism driven thereby and including a second member adapted to be moved in opposite directions and means adapted to drive said second member from said driving member in opposite directions and movable to neutral position, and means operating automatically upon said first-named means to cause the latter to operate said second member automatically in a reverse direction including a device for automatically operating on said first-named means to cause the latter to be in neutral position in which said driving member is out of driving engagement with said second member, a driving worm, a worm wheel adapted to mesh with said worm and having a mutilated portion normally registering with said worm, and a tension device eccentrically connected with said worm wheel and operatively engaging said first-named means and constructed and arranged to exert a driving force on said worm wheel for meshing the latter with said worm in the movement of said first-named means to neutral position and under the action of said worm wheel to exert thereafter force on said first-named means to condition the latter for driving said second member in said reverse direction.

5. The combination of a driving member, mechanism driven thereby and including a second member adapted to be moved in opposite directions and means adapted to

drive said second member from said driving member in opposite directions and movable to neutral position, and means operating automatically upon said first-named means to cause the latter to operate said second member automatically in opposite directions including a device for automatically operating on said first-named means to cause the latter to be in neutral position in which said driving member is out of driving engagement with said second member, a driving worm, a worm wheel adapted to mesh with said worm and having a mutilated portion normally registering with said worm, and a tension device operatively engaging said worm wheel and said first-named means and constructed and arranged to exert a driving force on said worm wheel for meshing the latter with said worm in the movement of said first-named means to neutral position and under the action of said worm wheel to exert thereafter force on said first-named means to condition the latter for driving said second member in said reverse direction.

6. The combination of a driving member, mechanism driven thereby and including a second member adapted to be moved in opposite directions and means adapted to drive said second member from said driving member in opposite directions and movable to neutral position, and means operating automatically upon said first-named means to cause the latter to operate said second member automatically in a reverse direction including a device for automatically operating on said first-named means to cause the latter to be in neutral position in which said driving member is out of driving engagement with said second member, a driving worm, a worm wheel adapted to mesh with said worm and having a mutilated portion normally registering with said worm, and a tension device eccentrically connected with said worm wheel and operatively engaging said first-named means and constructed and arranged to exert a driving force on said worm wheel for meshing the latter with said worm in the movement of said first-named means to neutral position and under the action of said worm wheel to exert thereafter force on said first-named means to condition the latter for driving said second member in said reverse direction.

7. The combination of a driving member, mechanism driven thereby and including a second member adapted to be moved in opposite directions and means adapted to drive said second member from said driving member in opposite directions and movable to neutral position, and means operating automatically upon said first-named means to cause the latter to operate said second member automatically in a reverse direction including a device for automatically operating

12. The combination of a driving member, mechanism driven thereby and including a second member adapted to be moved in opposite directions and means adapted to drive said second member from said driving member in opposite directions and movable through neutral position, and means operating automatically upon said first-named means to cause the latter to move automatically from one driving position through neutral position to a position for operating said second member in reverse direction including a tension device, mechanism controlled by said device in tensioned condition for shifting said first-named means to operative position for reversing the movement of said second member through the medium of said tension device, and releasable means engaging said last-named mechanism, said tension device when in normal position in which said first-named means are driving said second member exerting force on said last-named mechanism, resisted by said releasable means, and tending to condition the latter for operation, and in the operation of said last-named mechanism, following the release of said releasable means, becoming reversely tensioned for moving said first-named means to a position in which said second member is driven in a reverse direction.
13. The combination of a driving member, mechanism driven thereby and including a second member adapted to be moved in opposite directions and means adapted to drive said second member from said driving member in opposite directions and movable through neutral position, and means operating automatically upon said first-named means to cause the latter to move automatically from one driving position through neutral position to a position for operating said second member in reverse direction including a tension device, mechanism controlled by said device in tensioned condition for shifting said first-named means to operative position for reversing the movement of said second member through the medium of said tension device and releasable means controlled by said first-named mechanism and engaging said last-named mechanism, said tension device when in normal position in which said first-named means are driving said second member exerting force on said last-named mechanism, resisted by said releasable means, and tending to condition the latter for operation, and in the operation of said last-named mechanism, following the release of said releasable means, becoming reversely tensioned for moving said first-named means to a position in which said second member is driven in a reverse direction.
14. The combination of a driving member, mechanism driven thereby and including a second member adapted to be moved in opposite directions and means adapted to drive said second member from said driving member in opposite directions and movable through neutral position, and means operating automatically upon said first-named means to cause the latter to operate said second member automatically in a reverse direction including a device for automatically operating on said first-named means to cause the latter to be in neutral position in which said driving member is out of driving engagement with said second member, a driving gear, a second gear adapted to mesh with said driving gear and having a mutilated portion normally registering with said driving gear, and means operatively engaging said second gear and said first-named means and operating when said first-named means are moved to neutral position to exert a driving force on said second gear for meshing the latter with said driving gear and under the action of said second gear to exert thereafter force on said first-named means to condition the latter for driving said second member in said reverse direction.
15. The combination of a driving member, mechanism driven thereby and including a second member adapted to be moved in opposite directions and means adapted to drive said second member from said driving member in opposite directions and movable to neutral position, and means operating automatically upon said first-named means to cause the latter to operate said second member automatically in a reverse direction including a device for automatically operating on said first-named means to cause the latter to be in neutral position in which said driving member is out of driving engagement with said second member, a driving gear, a second gear adapted to mesh with said driving gear and having a mutilated portion normally registering with said driving gear, and means operatively engaging said second gear and said first-named means and operating when said first-named means are moved to neutral position to exert a driving force on said second gear for meshing the latter with said driving gear and under the action of said second gear to exert thereafter force on said first-named means to condition the latter for driving said second member in said reverse direction.
16. The combination of a driving member, mechanism driven thereby and including a second member adapted to be moved in opposite directions and means adapted to drive said second member from said driving member in opposite directions and movable to neutral position, and means operating automatically upon said first-named means to cause the latter to operate said second member automatically in a reverse direction.

- direction including a device for automatically operating on said first-named means to cause the latter to be in neutral position in which said driving member is out of driving engagement with said second member, a driving gear, a second gear adapted to mesh with said driving gear and having a mutilated portion normally registering with said driving gear, and a tension device operatively engaging said second gear and said first-named means and constructed and arranged to exert a driving force on said second gear for meshing the latter with said driving gear in the movement of said first-named means to neutral position and under the action of said second gear to exert thereafter force on said first-named means to condition the latter for driving said second member in said reverse direction.
17. The combination of a driving member, mechanism driven thereby and including a second member adapted to be moved in opposite directions and means adapted to drive said second member from said driving member in opposite directions and movable to neutral position, and means operating automatically upon said first-named means to cause the latter to operate said second member automatically in opposite directions including a device for automatically operating on said first-named means to cause the latter to be in neutral position in which said driving member is out of driving engagement with said second member, a driving gear, a second gear adapted to mesh with said driving gear and having a mutilated portion normally registering with said driving gear, and a tension device operatively engaging said second gear and said first-named means and constructed and arranged to exert a driving force on said second gear for meshing the latter with said driving gear in the movement of said first-named means to neutral position and under the action of said second gear to exert thereafter force on said first-named means to condition the latter for driving said second member in said reverse direction.
18. The combination of a driving member, mechanism driven thereby and including a second member adapted to be moved in opposite directions and means adapted to drive said second member from said driving member in opposite directions and movable to neutral position, and means operating automatically upon said first-named means to cause the latter to operate said second member automatically in a reverse direction including a device for automatically operating on said first-named means to cause the latter to be in neutral position in which said driving member is out of driving engagement with said second member, a driving gear, a second gear adapted to mesh with said driving gear and having a mutilated portion normally

registering with said driving gear, and a tension device eccentrically connected with said second gear and operatively engaging said first-named means and constructed and arranged to exert a driving force on said second gear for meshing the latter with said driving gear in the movement of said first-named means to neutral position and under the action of said second gear to exert thereafter force on said first-named means to condition the latter for driving said second member in said reverse direction.

19. The combination of a driving member, mechanism driven thereby and including a second member adapted to be moved in opposite directions and means adapted to drive said second member from said driving member in opposite directions and movable to neutral position, and means operating automatically upon said first-named means to cause the latter to operate said second member automatically in a reverse direction including a device for automatically operating on said first-named means to cause the latter to be in neutral position in which said driving member is out of driving engagement with said second member, a driving gear, a second gear adapted to mesh with said driving gear and having substantially diametrically opposed mutilated portions, one of which normally registers with said driving gear, and means eccentrically engaging said second gear and engaging said first-named means and operating when said first-named means are moved to neutral position from either of their operating positions to exert a driving force on said second gear for meshing the latter with said driving gear and under the action of said second gear to exert a force on said first-named means to condition the latter for driving said second member in reverse direction.

20. The combination of a driving member, mechanism driven thereby and including a second member adapted to be moved in opposite directions and means adapted to drive said second member from said driving member in opposite directions and movable to neutral position, and means operating automatically upon said first-named means to cause the latter to operate said second member automatically in a reverse direction including a device for automatically operating on said first-named means to cause the latter to be in neutral position in which said driving member is out of driving engagement with said second member, a driving gear, a second gear adapted to mesh with said driving gear and having substantially diametrically opposed mutilated portions one of which normally registers with said driving gear, and means in the form of a tension device eccentrically engaging said second gear and engaging said first-named means and operating when said first-named means

are moved to neutral position from either of their operating positions to exert a driving force on said second gear for meshing the latter with said driving gear and under the 5 action of said second gear to exert a force on said first-named means to condition the latter for driving said second member in reverse direction.

21. The combination of a driving member, mechanism driven thereby and including a second member adapted to be moved in opposite directions and means adapted to drive said second member from said driving member in opposite directions and movable 10 to neutral position, and means operating automatically upon said first-named means to cause the latter to operate said second member automatically in a reverse direction including a device for automatically operating 15 on said first-named means to cause the latter to be in neutral position in which said driving member is out of driving engagement with said second member, a device operated by said driving member while said 20 first-named means are in neutral position, and tension means actuated by said last-named device for automatically moving said first-named means to a position for reversing the movement of said second member.

22. The combination of a driving member, mechanism driven thereby and including a second member adapted to be moved in opposite directions and means adapted to drive said second member from said driving member in opposite directions and movable 25 to neutral position, and means operating automatically upon said first-named means to cause the latter to operate said second member automatically in a reverse direction including a device for automatically operating 30 on said first-named means to cause the latter to be in neutral position in which said driving member is out of driving engagement with said second member, a device operated continuously by said driving member, and tension means actuated by 35 said last-named device for automatically moving said first-named means through neutral position into a position for reversing the movement of said second member.

23. The combination of a driving member, mechanism driven thereby and including a second member adapted to be moved in opposite directions and means adapted to drive said second member from said driving member in opposite directions and movable 40 to neutral position, and means operating automatically upon said first-named means to cause the latter to operate said second member automatically in a reverse direction including a device for automatically operating 45 on said first-named means to cause the latter to be in neutral position in which said driving member is out of driving engagement with said second member, a device operated by said driving member while said first-named means are in neutral position, and tension means actuated by said last-named device for automatically moving said first-named means to 50 position for successively reversing the movement of said second member.

24. The combination of a driving member, mechanism driven thereby and including a second member adapted to be moved in opposite directions and means adapted to drive said second member from said driving member in opposite directions and movable 55 to neutral position, and means operating automatically upon said first-named means to cause the latter to operate said second member automatically in a reverse direction including a device for automatically operating 60 on said first-named means to cause the latter to be in neutral position in which said driving member is out of driving engagement with said second member, a device operated by said driving member while said first-named means are in neutral position, and tension means actuated by said last-named device for automatically moving said first-named means to 65 position for reversing the movement of said second member.

25. The combination of a driving member, mechanism driven thereby and including a second member adapted to be moved in opposite directions and means adapted to drive said second member from said driving member in opposite directions and movable 70 to neutral position, and means operating automatically upon said first-named means to cause the latter to operate said second member automatically in a reverse direction including a device for automatically operating 75 on said first-named means to cause the latter to be in neutral position in which said driving member is out of driving engagement with said second member, a device continuously operated by said driving member, and means, including a tension device, actuated by said second-named device for automatically moving said first-named means through neutral position to a position for reversing the movement of said second member.

26. The combination of a driving gear, a second gear for meshing with said driving gear and having a mutilated portion for registration with said driving gear, an element, the position of which is to be controlled, and a tension device operatively engaging said second gear and said element and in one position of said element exerting 80 force on said second gear to mesh it with said driving gear and in the driving of said second gear by said driving gear becoming reversely tensioned and exerting a force on said element for shifting the latter.

27. The combination of a worm, a worm- 85

wheel for meshing with said worm and having a mutilated portion for registration with said worm, an element the position of which is to be controlled, and a tension device operatively engaging said worm-wheel and said element and in one position of said element exerting force on said worm-wheel to mesh it with said worm, and in the driving of said worm-wheel by said worm exerting a force on said element for shifting the latter.

28. The combination of a driving gear, a second gear for meshing with said driving gear and having a mutilated portion for registration with said driving gear, an element the position of which is to be controlled, and a tension device eccentrically engaging said second gear and operatively engaging said element and in one position of said element exerting force on said second gear to mesh it with said driving gear and in the driving of said second gear by said driving gear becoming reversely tensioned and exerting a force on said element for shifting the latter.

29. The combination of a worm, a worm-wheel for meshing with said worm and having a mutilated portion for registration with said worm, an element the position of which is to be controlled, and a tension device operatively engaging said worm-wheel and said element and in one position of said element exerting force on said worm-wheel to mesh it with said worm and in the driving of said worm-wheel by said worm exerting a force on said element for shifting the latter.

30. The combination of a driving member, mechanism driven thereby and including a second member adapted to be moved in opposite directions and means to drive

said second member from said driving member in opposite directions alternately and movable to neutral position from either of its driving positions, and means operating automatically upon said first-named means to cause the latter to operate said second member automatically in a reverse direction including a device for automatically operating on said first-named means to cause the latter to be in neutral position in which said driving member is out of engagement with said second member and comprising a rock-member operated from said mechanism in opposite directions, respectively, in the movement of said second member in opposite directions, a driving gear, a second gear adapted to mesh with said driving gear and having opposed mutilated portions adapted to successively register with said driving gear and normally registering at one of said mutilated portions with said driving gear, a spring element operatively engaging said first-named means and eccentrically engaging said second gear, releasable resisting means operatively engaging said second gear, said spring element when said first-named means are in either of their driving positions exerting force on said second gear, resisted by said releasable resisting means, and tending to move said second gear into mesh with said driving gear and in the operation of said second gear, following the release of said releasable resisting means, becoming tensioned for moving said first-named means into a position for reversely driving said second member, and means controlled by said rock member for controlling the release of said releasable resisting means.

BARTON S. SNOW.
